UNITED STATES PATENT OFFICE.

DAVID BEDELL, OF SENECA FALLS, NEW YORK.

IMPROVED GATE-PULLEY.

Specification forming part of Letters Patent No. **28,146**, dated May 8, 1860.

To all whom it may concern:

Be it known that I, DAVID BEDELL, of Seneca Falls, in the county of Seneca and State of New York, have invented a new and Improved Reversible Gate-Pulley; and I do hereby declare that the following is a full and exact description thereof, reference being had to the accompanying drawings, in which—

Figure 1 is a side elevation of the pulley-frame, shown as attached to the gate-post. Fig. 2 is a plan view of the same. Fig. 3 is an elevation of a gate, showing the pulley and weight in operation.

Like letters refer to corresponding parts in all of the figures.

My improvement consists in an arrangement of pulleys and extension-bar for adapting the weight used for closing to the weight of the gate and adjusting it to either right or left hand gates.

As represented in the drawings, A is a metallic frame firmly attached to the gate-post B by screws, and further sustained by the diagonal brace J. A vertical pulley G is pivoted in the center of the front or projecting portion of the frame A, so as to turn freely on its axis. A horizontal pulley H is pivoted in the forked end of the bar E. This bar is held against the front side of the frame A by the thumb-screw b, which passes through a slot f longitudinally of the bar. This slot, being long, admits of increasing or diminishing the distance between the two pulleys, as may be required. The bar rests across a projecting part e on the frame, which forms its fulcrum or chief support in connection with the thumb-screw b.

The weight I, Fig. 3, is attached to a suitable chain or cord, which is passed over the vertical pulley G and around the horizontal one H and connected with the gate D in the usual manner, so that when opened the weight is drawn up, and in descending by its gravity closes the gate.

My invention is designed to apply to any gate or heavy door where such a device is needed, and as the power required varies so greatly with the size and weight it must be capable of adjustment thereto, as well as to the direction in which the gate or door opens, be it right or left. The former is provided for in the slotted extension-bar E, which carries the pulley H. By loosening the thumb-screw b and extending the bar it places pulley H (which is the fulcrum over which the power of the weight is applied to the gate) farther from the axis or center of motion of the gate, thereby increasing the power exerted by the falling weight, and by sliding this bar more or less the power can be adjusted to the resistance offered by the gate with great precision and with the slightest effort. To adapt it to the opening of gates in different directions, the bar E is made reversible. To this end another hole c for the thumb-screw b is provided on the opposite side of the pulley G, but in the same relative position, and the bar is reversed, bringing the pulley H in the position indicated by the dotted lines F in Fig. 1, by which it operates in the same manner as before, the pulley G being stationary, so that the only change is in the relative positions of the two. This forms a very simple, cheap, and effectual device for readily attaching a weight to gates in all situations and adjusting the power to close them efficiently.

What I claim as my invention, and desire to secure by Letters Patent, is—

The reversible extension-bar E, which bears the fulcrum-pulley H, constructed and arranged in combination with its frame or support A and in relation to the stationary pulley G and gate or door D, substantially as and for the purposes herein specified.

DAVID BEDELL.
